CLAIM

(22) Filed: **Aug. 5, 2013**

The ornamental design for a bow tie and handkerchief retail combination, as shown and described.

DESCRIPTION

(60) Division of application No. 29/428,061, filed on Jul. 25, 2012, which is a continuation-in-part of application No. 29/397,653, filed on Jul. 19, 2011, now Pat. No. Des. 690,077.

FIG. 1 is a front elevation view of a bow tie and handkerchief retail combination, with the bow tie being in an unfolded position, showing my new design;
FIG. 2 is a rear elevation view thereof;
FIG. 3 is a left side elevation view thereof; and,
FIG. 4 is a bottom plan view thereof.
The hanger, including a front locking bar thereof that is attached to a base portion of the hanger with a pair of posts, as well as inner folds of the handkerchief, shown in broken lines form no part of the claimed design.
